TRIP LATCH STAKE POCKET

Beta Vinson, Emporia, Va.

Application May 20, 1952, Serial No. 288,811

1 Claim. (Cl. 280—145)

1
This invention relates to logging vehicles, and more particularly to remotely controlled release means for the stakes of a logging vehicle to allow the stakes to be released when the vehicle is to be unloaded.

The main object of the invention is to provide a novel and improved stake releasing means for releasing the stakes in a logging vehicle from a remote position, whereby the vehicle may be unloaded without risk of injury to the operator, the improved means being simple in construction, being easy to install, and being reliable in operation.

A further object of the invention is to provide improved means for releasably supporting the stakes of a log-carrying vehicle, the means being arranged for simultaneous release of the stakes from a remote location, whereby the logs on a vehicle may be unloaded without risk of injury to the operator, the improved device involving inexpensive parts, being sturdy in construction, and being substantially positive in operation.

Further objects and advantages of the invention will become apparent from the following description and claim, and from the accompanying drawings, wherein:

Figure 1 is a fragmentary perspective view of the rear end portions of longitudinal frame members of a log-carrying vehicle equipped with improved stake supporting means according to the present invention, said supporting means being shown in locked position with a pair of stakes supported therein.

Figure 2 is a fragmentary enlarged top plan view of one of the stake-receiving pocket structures of Figure 1.

Figure 3 is a cross sectional view taken on the line 3—3 of Figure 2.

Figure 4 is a perspective detail view of one of the longitudinal plate members employed in a stake-receiving structure of Figure 1.

Referring to the drawings, 11 and 12 designate respective longitudinally extending frame members of a log-carrying vehicle, forming part of the vehicle body and being rigidly secured to the body by means not shown. Secured to the ends of the respective longitudinal frame members 11 and 12 are respective stake-receiving structures, each structure comprising a pair of longitudinally extending vertical plate members 13 and 14 secured to the opposite sides of the longitudinal frame member and extending a substantial distance beyond the end of the longitudinal frame member, to define a space between the projecting ends of the plate members 13 and 14 for re-

ceiving a vertical stake 15. The plate member 14 has rigidly secured thereto an eye member 16 and designated at 17 is a transversely extending vertical plate member which is hingedly connected to the eye element 16 by means of a loop 18 integrally formed on the end of the plate member 17 and engaging the eye element 16, as is clearly shown in Figure 2. The plate member 17 is formed with an aperture 20 through which is engageable a lug 22 formed on the end edge of the plate member 13.

The longitudinal vertical plate member 13 is formed with a pair of ribs or flanges 23, 23 to the rear portions of which are pivotally secured the respective arms of a yoke member 21, as by a vertical rivet 24. Pivoted between the opposite end portions of the flanges 23, 23, as by a vertical rivet 26 is a right-angled hook member 27 whose free arm is receivable within the yoke member 21, in the manner shown in Figure 2. Designated at 28 is a link bar which is pivotally connected to the end of the transverse plate member 17, as by an eye element 29 connected to said vertical plate member 17, as shown in Figure 2. The link member 28 comprises an elongated loop whose forward end portion is engageable around the shank portion of the hook element 27 in the manner shown in Figure 2, whereby the transverse plate member 17 will be held in the position of Figure 2. When the yoke member 21 is rotated clockwise, as viewed in Figure 2, to the dotted view position shown therein, the hook member 27 is released allowing said hook member to pivot counterclockwise and allowing the link member 28 to become disengaged from the hook. This releases the transverse plate member 17, allowing the stake 15 to fall out of its pocket under the weight of the logs piled on the vehicle body, as will be subsequently explained.

The yoke member 21 is biased counterclockwise toward locking position by a coiled spring 30 connecting said yoke member to the adjacent longitudinal vertical plate member 13, as shown in Figure 3.

Designated at 31 is a transversely extending rod member which is slidably mounted beneath the longitudinal frame members 11 and 12, as by respective pairs of U-shaped supporting brackets 32, 32 secured to the under surfaces of the longitudinal frame members 11 and 12 in transverse alignment, one end of the bar 31 being formed with the eye loop 33. Each yoke member 21 is formed with the rearwardly extending arm 34, and the arms 34 are connected by respective link bars 35 to the transversely extending, slidable bar

31, as shown in Figure 1. It will thus be readily apparent that by moving the bar 31 to the left, as viewed in Figure 1, the respective yokes 21 will be rotated clockwise, as viewed in Figure 1, releasing the respective hooks 27, and hence releasing the respective transverse vertical plate members 17. As above explained, when the transverse plate members 17 are released, the weight of the logs on the vehicle body causes the stakes 15 to fall out of their pockets and allows the logs to roll off of the vehicle body. Obviously, the release bar 31 may be actuated from a remote point, as by connecting a length of cable to the loop 33, whereby the operator may stand at a safe distance from the vehicle and release the stakes 15 thereof by pulling on the cable.

While a specific embodiment of an improved stake releasing structure for log-carrying vehicles has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

In a vehicle of the type having spaced parallel log supporting bolsters means for releasably supporting stakes on the bolsters in vertically extending position adjacent opposite ends of said bolsters and for simultaneously releasing the stakes adjacent one side of the vehicle and permitting them to fall away from the bolsters, said means comprising pairs of spaced parallel side plates carried by the bolsters and extending longitudinally therefrom to define with the adjacent ends of the bolsters stake receiving recesses, an end plate carried by one side plate of each pair of side plates to move in an arcuate path from an active position in which it

extends across the adjacent ends of its respective pair of side plates and in closing relation to the end of the recess defined between the side plates and the bolster to an inactive position in which the end of the recess is wholly open, a lug carried by the opposite side plate and extending longitudinally therefrom adjacent the open end of the recess, the end plate having an opening extending therethrough for receiving the lug when the end plate is in active position, an elongated loop carried by the end plate in spaced relation to the recess, a hook carried by the plate carrying the lug for movement in an arcuate path adjacent the side of said plate remote from the bolster, said hook being adapted to extend through the loop to hold the end plate in active position, a yoke carried by the plate carrying the lug for movement in an arcuate path which intersects the path of movement of the adjacent hook for holding said hook in loop retaining position, a spring carried by the bolster and connected to the yoke for moving said yoke into hook retaining position, a lever carried by each yoke and projecting outwardly therefrom for moving its respective yoke in its arcuate path into hook releasing position, an operating rod mounted on the bolsters for shifting movement transversely thereof, and means carried by the rod and connected to the levers adjacent ends of the bolsters for moving the levers against the effort of the springs to release the hooks.
